UNITED STATES PATENT OFFICE.

RICHARD F. BRIDEWELL, OF SAN FRANCISCO, CALIFORNIA.

STREET-CAR PROPULSION.

SPECIFICATION forming part of Letters Patent No. 279,325, dated June 12, 1883.

Application filed January 20, 1882. (No model.)

To all whom it may concern:

Be it known that I, RICHARD F. BRIDEWELL, of San Francisco, in the county of San Francisco and State of California, have invented 5 certain new and useful Improvements in the Propulsion of Street-Cars; and I do hereby declare the following to be a full, clear, and exact description of the invention, such as will enable others skilled in the art to which it pertains to make and use it, reference being had to the accompanying drawings, which form part of this specification.

My invention relates to an improvement in the propulsion of street-cars; and it consists 15 in the combination of a suitable curved frame, which is to be placed at every curve in the road, and an endless chain, which is provided with large bearing-rollers, which serve as guides for the cable in passing around the curve, suitable small friction-rollers which bear against 20 the curved frame, suitable spurs formed as a part of the links for the grip of the car to strike against, and suitable small supporting-pulleys which run upon opposite sides of the 25 flange formed on the inner side of the bed-piece, so as to keep the rollers pressed against the bed, as will be more fully described hereinafter.

The object of my invention is to have the 30 cable bear only against large pulleys, which carry the cable sufficiently far away from the bed-frame to prevent the grip from touching the frame, and which rollers revolve idly upon their pivots until the grip of the car strikes 35 one of the projecting spurs of the endless chain, when the whole chain will be moved along until the grip has passed beyond the curve, when all of the chain comes to a rest again, with the exception of the large guiding-pulleys.

40 Figure 1 represents a plan view of my invention. Fig. 2 is a vertical section of the bed-frame. Fig. 3 is a detail view. Fig. 4 is a front elevation of my invention.

At each curve in the road there is built a 45 suitable foundation of brick or stone, and upon the top of this foundation is secured the bed A, which has a suitable wide flange or projection, B, which extends upward any suitable distance. This flange is placed sufficiently far 50 inward from the edge C of the bed to form a

track upon which the supporting-rollers travel. Bolted or otherwise secured in any suitable manner to this bed-piece A is an iron frame, D, which is bent over at its top, so as to form a bearing-surface, E, for the friction-roller F. 55 The two parts B E form the bearings against which the friction-rollers F of the endless chain bear while it is in motion. This endless chain is composed of a number of links, G, of any suitable length, which are united 60 together by the pins H. In between the friction-rollers, upon the pins H, are placed the large guiding-pulleys I, having grooved edges, so as to catch the driving-cable J and guide it around the curve. These pulleys I are made 65 sufficiently large to carry the cable J sufficiently far outward from the frame to prevent the grip of the car from coming in contact with the frame, and these pulleys I turn idly upon the pins H while no car is passing around the 70 curve. These pulleys serve simply as guides for the cable, and serve no other purpose. As the pressure of the cable is brought to bear 75 entirely against these large pulleys I, as the cable passes around the curve the whole pressure is brought to bear upon the pins H, and these pins H force the small pulleys F against the two parts B E of the frame. These pulleys F remain stationary against their bearing-places upon the frame until the chain is started 80 in motion, and then the whole pressure of the cable is transferred through them to the frame. Each one of the links G, which has its end attached to the pin or rod which passes through the large pulleys I, has a spur or projection, 85 L, formed upon it; and which spur or projection extends outward beyond the circumference of the large pulley I. This spur L serves for the grip of the car to strike against, and when the grip comes in contact with one of 90 these spurs L the forward movement of the car is communicated to the entire endless chain. No sooner does the grip strike against the spur than the large pulley I will stop its movement, and the small pulleys F then travel 95 with the same speed as the cable.

By means of the construction above described the car can be carried at full speed around the curves in the line, and can be stopped or started at any portion of the curve in the road.

The pins or axles H, which pass down through the pulleys F and I, pass below the under sides of the bottom links, G, and these bottom links rest upon the tops of a double series of rollers, 5 N, which are united together by means of the links P, which separate them. These rollers are arranged in pairs, and have the same axles or bearings, O, which pass through the links P, as shown.

10 Upon the top of the bed-piece, upon the inner side, is formed a suitable flange, Q, and these rollers N, coupled together in pairs, travel upon opposite sides of this flange for the purpose of keeping the endless chain in contact 15 with the frame, instead of having it assume a straight line from one end of the frame to the other. Should the cars pass up and down upon the same street, there will be two of these frames and endless chains arranged at each 20 bend in the road, one for the cable that goes up and the other for the cable that comes back. The frames are of course to be placed below the level of the street, as is always the case where the cars are to be drawn along by traction.

25 It will be seen from the above arrangement that about one-half of all the large grooved rollers I will be turning idly upon their axles from frictional contact with the moving cable, 30 while the other portion of the pulleys remain at rest. When the chain is once started in motion by the grip of a car coming in contact with one of the spurs of the endless chain all of the pulleys I will be moved along with the 35 chain at the same speed that the cable is moving.

Having thus described my invention, I claim—

1. The combination of a suitable curved guiding-frame and an endless chain provided with

a series of large pulleys which turn idly upon their axles from frictional contact with the cable, but which are moved along with the endless chain when the grip of the car starts the chain in motion, substantially as shown. 45

2. The combination of the curved bed-frame provided with the bearings B E, and an endless chain provided with the small pulleys F, the large pulleys I, spurs for the grip to strike against, and suitable supporting-rollers, substantially as described. 50

3. The combination of the curved guiding-frame provided with the guiding-flange A, the supporting and guiding rollers N, connected together in pairs by means of the links P, and the endless chain composed of the links G, rollers F, and pulleys I, substantially as set forth. 55

4. The combination of a curved guiding-frame and an endless chain which is provided with large guiding-pulleys for the cable to bear 60 against, and spurs for the grip of the car to strike against, the parts being so constructed that the chain remains stationary until the grip of the car comes in contact with one of the spurs, when the whole of the endless chain is 65 set in motion, substantially as specified.

5. A curved bed-frame around which the endless chain is passed, the said bed-frame being provided with the bearing-surfaces B E, and a guiding-flange, Q, in combination with 70 a suitable endless chain which is passed around the said frame, substantially as shown and described.

In testimony whereof I affix my signature in presence of two witnesses.

RICHARD FRANCIS BRIDEWELL.
